US00D351849S

United States Patent [19]

Cheung et al.

[11] Patent Number: Des. 351,849

[45] Date of Patent: ** Oct. 25, 1994

[54] **ROBOTIC SHOULDER**

[75] Inventors: **Victor Cheung**, Arlington; **Amy Potts**, Somerville, both of Mass.

[73] Assignee: **Barrett Technology, Inc.**, Cambridge, Mass.

[**] Term: **14 Years**

[21] Appl. No.: **10,562**

[22] Filed: **Jul. 9, 1993**

[52] U.S. Cl. **D15/199**

[57] **CLAIM**

The ornamental design for the robotic shoulder, shown and described.

DESCRIPTION

FIG. 1 is a side elevational view of the left and the right sides of the robotic shoulder according to this invention;

FIG. 2 is an elevational view of the front and back views of the robotic shoulder according to this invention;

FIG. 3 is a top plan view of the robotic shoulder of FIG. 2;

FIG. 4 is a bottom plan view of the robotic shoulder of FIG. 2;

FIG. 5 is a perspective view, with the robotic shoulder shown in a minus 20 degree angle;

FIG. 6 is a perspective view, with the robotic shoulder shown in a plus 45 degree angle; and,

FIG. 7 is a perspective view, with the robotic shoulder shown in a plus 120 degree angle.

FIG. 3

FIG. 1

FIG. 2

FIG. 4

FIG. 5

FIG. 6

FIG. 7
